(57) **CLAIM**

The ornamental design for a fluid dispensing closure as shown and described.

DESCRIPTION

FIG. 1 is a top perspective view of a fluid dispensing closure according to the invention.

FIG. 2 is a bottom perspective view of the fluid dispensing closure of FIG. 1.

FIG. 3 is a top view of the fluid dispensing closure of FIG. 1.

FIG. 4 is a bottom view of the fluid dispensing closure of FIG. 1.

FIG. 5 is a left side view of the fluid dispensing closure of FIG. 1.

FIG. 6 is a right side view of the fluid dispensing closure of FIG. 1.

FIG. 7 is a rear side view of the fluid dispensing closure of FIG. 1.

FIG. 8 is a front side view of the fluid dispensing closure of FIG. 1.

FIG. 9 is a cross-sectional view of the top perspective view of the fluid dispensing closure of FIG. 1, taken in the direction of 9-9.

FIG. 10 is a cross-sectional view of the bottom perspective view of the fluid dispensing closure of FIG. 2, taken in the direction of 10-10.

FIG. 11 is a cross-sectional side view of the fluid dispensing closure of FIG. 13, taken in the direction of 11-11; and, FIG. 12 is an enlarged cross-sectional view of a portion of the fluid dispensing closure of FIG. 11.

In the drawings, the evenly spaced broken lines show portions of a fluid dispensing closure that form no part of the claim, the dash-dot-dash broken lines represent boundaries of the claimed design and form no part thereof, and the long dash-double dot lines represent a sectional designation that forms no part of the claim.
